UNITED STATES PATENT OFFICE

RANDOLPH F. HALL, OF ITHACA, NEW YORK

AIRPLANE

Application filed April 5, 1928. Serial No. 267,625.

This invention relates to certain improvements in airplanes; and the nature and objects of the invention will be readily recognized and understood by those skilled in the aeronautical art in the light of the following explanation and detailed description of the accompanying drawings illustrating what I at present consider to be the preferred embodiments or mechanical and aero-
10 dynamical expressions of my invention from among various other types, forms, arrangements, combinations, and constructions of which the invention is capable within the spirit and the scope thereof.

15 Certain types of airplane wings or lift surfaces utilize the principle of the displacement of air through slots and/or passages to increase the lift developed by such wings, and to substantially eliminate or materially
20 reduce the possibility of the so-called "stall" under low-speed, high angle of attack, or high-lift conditions. Generally such types of wings provide for rendering the slots and/or the air displacement passages opera-
25 tive under and in order to develop the high-lift conditions, and for rendering the same inoperative under and to permit of developing high-speed, low angle of attack condi-
30 tions, either through the medium of manual-
35 ly controlled means, or through the medium of automatically controlled means. The means for converting the wings from the high-lift conditions to the high-speed, low attack angle conditions, usually, although not necessarily, take the form of vanes, flaps, or auxiliary surfaces which, whether manually or automatically controlled, function to render the slots and/or passages operative or
40 inoperative under the desired conditions, and when rendering the slots and/or passages inoperative are preferably designed and arranged to convert or form the wing to relatively high-speed characteristics.

45 The present invention contemplates and provides for the semi-automatic operation and control, that is, an operation and control which may be partially manual and partially automatic, of the means for rendering
50 the slots and/or air displacement passages

operative and inoperative, with the objects in view from among others, of securing simplicity of design and construction, with reliability of operation, positiveness of action, and the various factors attendant thereto and resulting therefrom.

One characteristic of the invention consists in the semi-automatic control and operation in which the automatic operation is dependent upon and is initiated by and follows the manual control and operation as a result of conditions set up and established by the manual control, so that the conversion of the wing or lift surface through the rendition of the slots and/or air displacement passages, 65 operative and inoperative, is under the arbitrary control of the manually operated and controlled means, but is carried out and completed by the automatic means.

Another characteristic and feature of the invention resides in the employment of the foregoing semi-automatic principle of control and operation with wings or lift surfaces of the slotted and/or air displacement passage types, and with high lift wings of 70 the flap types, or in combinations of the slot and/or air displacement passage and flap types.

A further feature of the invention is found in the mounting and arrangement of control surfaces for a wing on and in cooperative relation with the means for converting the wing to the high lift or to the high speed conditions, by which such control surfaces are 75 operable independently of and simultaneously and during the operation and control of the wing converting means.

Another feature of the invention consists in the design, mounting and operation of the automatically controlled and operated means 80 of the invention for converting or rendering the slots and/or air displacement passages operative or inoperative to obtain the desired high lift, or obtain the high speed, 85 conditions of the wing.

A further characteristic and feature of the invention is found in the relative and cooperative mountings and arrangements of the manually controlled and operated means and the automatically operated means, on and in 90 100

combination and relation to the wing or lift surface and the air displacement slots and/or passages thereof, in order to secure the efficient functioning and operation of the wing.

With the foregoing general characteristics, features, and objects, as well as certain others in view which will be readily apparent and understood from the following explanation, the invention consists in certain features in design, arrangement, combinations, and operation of elements and parts, as will be more fully and particularly referred to and specified hereinafter.

Referring to the accompanying drawings:

Fig. 1 is a vertical, transverse and more or less diagrammatical section through a wing of the air displacement slot or passage type embodying the principles and certain features of the invention, and showing the semi-automatic passage controlling means in open position for the high lift condition of the wing, the means being shown in closed position by dotted lines.

Fig. 2 is a vertical, transverse section, more or less diagrammatical, through another form and arrangement of the semi-automatic passage controlling means in open position for the high or increased lift condition, the means being shown in closed position in dotted outline.

Fig. 3 is a view similar to Fig. 2, but showing an arrangement and mounting of lateral control surfaces of ailerons thereon operatively carried by the manually controlled rear passage closing vanes or flaps of the wing.

Fig. 4 is a view similar to Fig. 3, showing a modified form of wing thereof, in which forward flaps are interconnected with and for operation by the rear passage closing vanes or flaps of the wing.

As an example purely and not as a limitation, I have selected and disclosed herewith for the purpose of explaining the principles and the various features of my invention in order to enable those skilled in the aeronautical art to understand the same, an airplane wing or lift surface of the type having an air displacement passage formed therein and extending rearwardly therethrough. The type of wing here shown happens to take the form and present the principle of the wings disclosed in my United States Patent No. 1,559,091, dated October 27, 1925, in which an air displacement passage is formed through a wing between spaced airfoils. However, the present invention is in no sense restricted or limited to application to, or embodiment in the general type of wing, or the particular form of such type here shown, but is of broad and general application to wings or lift surface of the slotted and/or air displacement passage types, as well as to wings or surfaces of the flap

or variable camber types for securing increased lift, all of which will be readily recognized by those skilled in the art after the following description and explanation.

An aerodynamical and mechanical adaptation of the broad principles and certain features of the invention is presented by Fig. 1 of the accompanying drawings, in which a wing W is more or less diagrammatically shown as embodying spaced upper and lower airfoils 10 and 11 providing an air displacement passage 12 extending rearwardly therebetween. The form of the wing W here shown provides the upper airfoil 10 as of relatively thin section terminating forwardly in the downwardly extending relatively thick nose section 14 forming the leading edge portion of the wing; and the lower airfoil 11 as of considerably less chord than upper airfoil 10 and spaced in fixed position below and intermediate the upper airfoil 10, but to the rear of and relatively within the horizontal plane of the lower surface of the wing leading edge portion or section 14, of the upper airfoil. The airfoils 10 and 11 are suitably fixed together in any desired manner, forming no part of the present invention, as for example, by the usual or any desired arrangement of transverse ribs or spacing and connecting trusses or structures (not shown) to provide the wing W having the air displacement passage 12 extending therethrough, and opening at its forward inlet end downwardly through the lower surface of wing W between the leading edge of airfoil 11 and the wing leading edge portion 14 formed by the upper airfoil 10. The passage 12 is open and provides for outlet or discharge therefrom through the rear of the wing W at the under side of airfoil 10, and between airfoil 10 and the lower airfoil 11, as will be clear by reference to Fig. 1, of the drawings.

In the particular example hereof means are provided for closing the ends of passage 12 to convert the wing to present a single substantially unbroken airfoil section, and for opening the passage to permit displacement of air therethrough to increase the lift developed by the wing, as will be understood by those skilled in this art; and in accordance with the present invention such means are semi-automatically controlled and operated.

A vane or airfoil 20 is mounted in position across the forward inlet end of passage 12, between leading edge section 14 and the leading edge of the lower airfoil 11. This vane 20 is pivotally mounted for swinging or rotation around a longitudinal axis provided by a suitable shaft, tube, or the like 21, so that, in one position, shown in dotted lines, vane 20 is disposed across and closing the inlet end of passage 12, extending between leading edge section 14 and airfoil 11, while

in open position the vane is swung to extend outwardly and forwardly from the passage 12 to open this passage for entry of air thereto, the vane by its open position directing 5 and tending to force entry of air into the passage, as shown in Fig. 1.

The vane 20 in this instance is manually controlled and operated by any suitable or desired mechanism, such as that diagrammatically shown in Fig. 1, and embodying a 10 lever 22, carried at any suitable point on an airplane and connected at one end on shaft 21 which carries and rotates vane 20. A suitable locking quadrant or the like 23, is 15 provided by which the lever 22 can be releasably secured in the desired position through the medium of a dog 24.

A flap or the like 30 is pivotally mounted along the trailing edge of lower airfoil 11, 20 in rearward and airfoil contour continuation thereof, and this flap in position swung upwardly, as shown by dotted lines in Fig. 1, meets and engages the trailing edge of upper airfoil 10, to close the rear or discharge end 25 of passage 12, and to carry out the contour of the single wing section formed by the upper and lower airfoils with vane 20 and flap 30 swung to their positions closing the passage 12 and converting the wing W to a 30 single airfoil. (See dotted line positions of Fig. 1.) The flap 30, following the principles of the invention is automatically controlled and operated, and in the present instance is assisted through the medium of an 35 expansion spring 31, which is connected at one end on the interior of the wing forwardly of flap 30, in the example hereof to upper airfoil 10, and at its rear end is connected to a suitable horn or crank 32 fixed to and ex- 40 tending upwardly from the forward section of the flap 30. The arrangement of spring 31 is such that it normally draws and maintains flap 30 in raised position closing the rear or discharge end of passage 12, but upon the 45 building up of pressures in passage 12 by the entry of air thereto, the flap is forced downwardly against the tension of spring 31 to passage opening position, as well as to position increasing the camber of the lower air- 50 foil 11. (See the full line positions of Fig. 1.)

In operation and use, the wing W as described above, for high speed, low-attack angle conditions of flight, is operated with 55 the forward, manually operated vane 20 closed by lever 22, in the dotted line position of Fig. 1. With vane 20 closed, entry of air into the displacement passage 12 is cut off, and the spring 31 maintains the rear 60 flap 30 in raised position closing the rear end of the passage, and completing the conversion of wing W to a single airfoil section, as will be readily understood. When it is desired to increase the lift of wing W for high 65 lift or high attack angle conditions of flight,

the vane 20 is manually swung, through lever 22, to open position shown in full lines in Fig. 1, and in this open position air flows into passage 12, aided by the position of vane 20, and builds up pressure in the passage, whereupon the rear flap is operated and automatically swung downwardly against the tension of spring 31 to complete the conversion of the wing to high lift, passage operative, 70 condition. 75

To reconvert the wing to high speed condition, the vane 20 is manually swung to closed position 12 and stop flow of air therethrough, which destroys pressure on rear flap 30 and permits spring 31, aided by the pressure on the under side of flap 30, to automatically close or raise flap 30 and close the rear of passage 12 and complete the conversion of the wing for high-speed, low angle operation. In the foregoing manner a semi-automatic 80 control results in which the operation of the wing is arbitrarily manually controlled and initiated to cause a following, dependent and automatic operation completing the conversion or change in the wing to and from high 85 lift or high angle of attack operation. 90

The invention provides for maintaining the automatically controlled and operated rear flap 30 in fixed position after it is swung downwardly in passage opening position, until the manual operation of the forward vane 20 to close the forward inlet end of passage 12, which manual operation releases the rear flap for automatic return thereof to closed position. In the particular example of Fig. 1, a spring member or catch 33 is fixed to and depends downwardly and rearwardly from the fixed lower airfoil 11 adjacent the trailing edge thereof, and this spring member is so formed as to have a depression therein providing a seat for engaging a member. The rear flap 30 is provided with a depending finger or projection 34, which is fixed in such position thereon as to engage the spring member 33 and snap into the depression thereof when flap 30 is swung downwardly to open position, as clearly shown by full lines in Fig. 1. The spring member 33 engages finger 34 and retains flap 30 in fixed, lowered, and passage opening position. 100 105 110 115

In order to release flap 30 from member 33, a cable, rod or the like 35 is connected to member 30 and extends forwardly and is connected to a horn or crank 25 depending from and movable with the manually operable forward vane 20. The arrangement of cable 35 is such that in open position of vane 20, the spring member 33 takes a position for retaining engagement with flap finger 34, but upon swinging of vane 20 to passage closing position the spring member 33 is drawn or sprung forwardly by cable 35 to release finger 34 and permit of automatic operation of flap 30 to closed position. 120 125

Attention is here directed to the fact that, 130

the resilient or spring means in the automatic operation of the passage and/or slot opening and closing vanes or flaps, such as rear flap 30, of Fig. 1, are properly designed 5 and arranged so as to maintain the vanes or flaps in proper wing relation for varying conditions encountered. The invention recognizes and contemplates the effect or influence of such factors as flap location, pivot 10 point, balance surface, passageway proportions, flap weight, attitude, airspeed and general design, on such spring means, and hence various other designs, types, mountings and arrangements are included within the invention. 15

A different and modified arrangement of the invention is presented by Fig. 2 of the drawings, in which the wing W is utilized, comprising the upper airfoil 10, lower airfoil 20 11' and air displacement passage 12, extending therebetween, all as explained in connection with Fig. 1 of the drawings. In the present instance, the lower airfoil 11' of wing W is of complete airfoil section and contour, 25 although not so limited, while the wing leading edge portion 14' formed by the depending relatively thick nose section of upper airfoil 10, is provided with a vertically-disposed slot or slots 14'', as the case may be, extending 30 from the inner side thereof forwardly, and rearwardly inclined, all for a purpose appearing hereinafter. The forward inlet or intake end of the displacement passage 12, at the rear of leading edge portion 14' through 35 the lower or under surface of wing W, is controlled and opened or closed by an automatically controlled and operated vane or flap 40, while the rear or discharge end of passage 12 is opened and closed, in accordance 40 with the invention, by a manually controlled vane or flap 50, upon which, in the present instance the automatic operation of forward vane 40 is dependent.

The forward automatically controlled and 45 operated vane 40 for opening or closing the intake end of discharge passage 12, is pivotally mounted in this instance along the forward edge thereof, to and along the lower inner edge portion of the wing leading edge 50 14', across slot or slots 14'' therein, as clearly shown in Fig. 2. The vane 40 is swingable vertically to lowered passage closing position, as shown in dotted lines in Fig. 2, extending across and between the leading edge 55 14' and lower airfoil 11, to form a portion of and carrying out the lower surface contour of wing W. The vane 40 is of such a chord that in lowered passage closing position, the trailing edge thereof is spaced forwardly 60 from the leading edge of the lower airfoil 11', to form and provide a gap or opening 41 through the under or lower surface of wing W into passage 12, as will be explained more fully hereafter.

65 The automatic operation of vane 40, is ob-

tained in the present example through the medium of spring means, which in the specific instance hereof takes the form of an expansion spring 42 mounted longitudinally in the slot 14'' of section 14', secured at one end to the upper airfoil 10, or the upper inner wall of section 14' thereof, and at its opposite end to a crank, arm, or the like 43 extending upwardly and forwardly from the forward portion of vane 40 into the slot 14''. The arrangement of spring 42 is such that it normally draws crank 43 rearwardly and upwardly in slot 14'', to swing and maintain the pivotally mounted vane 40 in lowered passage closing position, a stop 44 being provided 70 against which crank 43 engages to limit downward swinging of the vane and insure proper lowered position of the vane with respect to lower airfoil 11'. With this arrangement and mounting of vane 40 and spring 42, the vane is readily swingable upwardly and forwardly into the wing, against the tension of spring 42, to position opening passage 12 for entry of air thereinto, as shown by full lines 75 in Fig. 2.

The manually controlled and operated rear vane or flap 50, in this example takes the form of an aerofoil or lift section and is pivoted on a longitudinal axis 51, intermediate the leading and trailing edges thereof, with the 80 portion of the vane or flap forward of its axis forming a balance surface therefor to reduce operating forces and eliminate possible flutter. The flap 50 is mounted and disposed in position between and extending 85 rearwardly from and beyond the trailing edges of the upper and lower airfoils 10 and 11, and in normal horizontally disposed position thereof, shown in dotted lines in Fig. 2, substantially closes the rear or discharge 90 end of displacement passage 12, while the upper and lower surfaces of this flap 50 form rearward continuations of the upper and lower airfoils 10 and 11, to carry out and 95 complete the contours and airfoil section of the wing W to present the wing as the single airfoil section for high-speed, low-angle condition, as will be readily understood. Preferably, as shown by Fig. 2, the upper airfoil 10 has the trailing edge portion thereof cut 100 away, or provides the trailing edge portion thereof along flap 50 disposed at the forward or balance surface thereof, so that flap 50 forms the rearward continuation in closed 105 position of the upper surface of airfoil 10. 110

The rear vane or flap 50 is swingable downwardly on its axis 51 to the position shown in full lines by Fig. 2, and in this position opens the rear or discharge end of passage 12, to provide an outlet between the raised forward 115 or balance portion of the flap and the trailing edge of lower airfoil 11', while at the same time increasing the camber of the wing 120 W. The operation or swinging of flap 50 is carried out manually through the medium 125 130

of any suitable or desired mechanism such as that diagrammatically indicated in Fig. 2, and comprising a hand lever 52 fulcrumed at 53 intermediate its length, and pivotally connected at its free end by a link 54 with a depending horn or crank 55 secured on the flap or vane 50. Obviously, and the invention so contemplates and includes, the manual operating mechanism for flaps 50 on the wings W of an airplane can be of the conventional aileron operating type to secure a differential operation of the flaps 50 on opposite wings W, for lateral control, and also for securing a simultaneous and equal raising or lowering 15 of such flaps on opposite wings.

In the high-speed, low incidence or attack angle conditions of flight with the wing W embodying the form and arrangement of the invention presented by Fig. 2, the manually controlled and operated rear flap or surface 50 is swung to its substantially horizontal, passage closing position, shown in dotted lines, and the forward, automatically controlled and operated vane 40 assumes 25 and is maintained, through the action of the spring 42, in downwardly swung position closing, with the exception of gap 41, the forward inlet end of air displacement passage 12, as indicated by dotted lines in Fig. 2. 30 The wing W is thus converted to and presents a single, substantially unbroken airfoil section or lift surface with the air displacement passage closed and rendered inoperative by the forward and rear vanes or flaps 35 40 and 50.

When it is desired to increase the lift of wing W and create the low-speed, high-lift conditions of operation, the lever 52 is operated to swing rear vane or flap 50 downwardly to the position shown by full lines in Fig. 2, which increases the camber of the wing, while at the same time opening the rear or discharge end of passage 12 for displacement and flow of air therethrough and therefrom. The increase in wing camber by rear flap 50 reduces airflow velocity on the under side of wing W with a resulting increase in under pressure, which increase in pressure overcomes the force of spring 42 and the weight of vane or flap 40, thereby raising or swinging flap 40 upwardly to the full line position of Fig. 2, and permitting flow of air into and displacement through passage 12, the discharge end of which passage is 55 opened by rear flap 50. The wing W, thereupon functions and operates at an increased lift but lower speed by the action of the airflow upon both the upper and lower airfoils 10 and 11', aided by the increased camber of 60 the wing contributed by rear flap 50.

In order to convert the wing W of Fig. 2, from the low-speed, high-lift condition, to the high-speed, low angle condition, the rear flap 50 is raised by operation of lever 52, to 65 the dotted line position closing passage 12

and decreasing or eliminating the increased camber given the wing by the flap in lowered or depressed position. Raising flap 50 closes passage 12 against flow of air therethrough and by the reduction in camber also increases 70 velocity of airflow at the under side of the wing with resultant decrease of pressure acting upwardly on vane 40, which with the stoppage of flow through passage 12, enables the spring 42 to swing the vane 40 to lowered 75 position, as shown by dotted lines, thus completing automatically the conversion of the wing initiated by the manual operation of the rear vane or flap 50.

The gap 41 between forward vane 40 and lower airfoil 11' provides for initial flow of air into passage 12 to assist in opening vane 40, as the rear of passage 12 is opened by the lowering of rear flap 50. The necessity for such gap is dependent upon certain factors 85 and the general design of the wing and the forward vane 40, and the invention is not restricted to the provision of such an initial air flow gap or opening.

In Fig. 3 of the drawings, an aileron or lateral control surface arrangement and mounting of the invention, is disclosed applied to a manually operated rear flap 50 for the form of wing W of Fig. 2. According to this feature of the invention the rear flap 50 is provided with an aileron or control surface 60 pivotally mounted and carried thereon in the usual manner and forming a portion of the trailing or rear section of flap 50. The aileron 60 is provided with the usual control or operating horn 61, by which the same can be vertically swung on flap 50. A rock or torque shaft 62 is mounted longitudinally of the upper airfoil 10 on the under side thereof within passage 12, in the present instance, and forwardly of rear flap 50, a shield 63 being preferably provided along and over the shaft 62 within passage 12. A crank 64 is fixed on shaft 62, and extends upwardly and swingably through and above upper airfoil 10. The upper free end of crank 64 is connected and coupled with the upper end of the aileron control horn 61 by a link 65 extending between and pivotally connected with horn 61 and crank 64. The torque shaft 62 is coupled operatively with the usual pilot's control for rocking to swing crank 64 and through link 65, raise and lower aileron 60, and where ailerons 60 are mounted in the usual manner on opposite wings of an airplane the conventional differential operation thereof is carried out for lateral control.

With the torque shaft 62 held stationary by the pilot, for example in the neutral aileron position, then lowering or depressing of the rear flap 50 to convert wing W to high lift operation, will cause the aileron or ailerons 60 to automatically rise with respect to the flap 50 and remain in their initial posi-

tion with respect to the wing W, because the link 65 remains in fixed relation with and to crank 64. The aileron 60 is thus independent of the operation of flap 50 and its 5 operation and positions, and is independently operable by the pilot for lateral control with the flap 50 in either raised or lowered positions. The aileron 60 thus permits of effective and efficient lateral control with 10 the flap 50 in lowered position and particularly in the conditions approaching stall, as will be understood by those skilled in the art. Through such ailerons 60 and their control and operating mechanism, the differential 15 operation of rear flaps 50 for securing lateral control becomes unnecessary and the rear flaps are operated by the separate manual control mechanism 52-54-55 for simultaneous operation of the flaps on 20 opposite wings. It is of course understood that where the rear flaps 50 do not extend or occupy the entire span of wing W, then if desired or found expedient the usual mounting of an aileron on the wing entirely 25 independent of and removed from flap 50 is contemplated, or that where the differential control of flaps 50 referred to in connection with Fig. 2, the use of ailerons 60 is not required.

30 An arrangement of plural and interconnected flaps including, and for manual control through rear flap 50 of a wing of the form of Fig. 2, is presented in Fig. 4. In this arrangement, the lower airfoil 11' of 35 wing W has a flap or vane 70 pivotally mounted thereon and forming a portion thereof, with flap 70 swingable downwardly from normal raised position alined with airfoil 11', as shown by full lines in Fig. 4. The 40 flap 70 is interconnected and operated by and simultaneously with and from rear flap 50, through the medium of a link 71 pivotally connected to and between depending crank 72 on flap 50 and depending crank 45 73 on flap 70 of airfoil 11'. The arrangement and relative mounting of cranks 72 and 73, with link 71, is such that, with the rear flap 50 in its raised dotted line position, the flap 70 is raised in its normal position 50 alined with and in lower airfoil 11' of the wing W, while lowering of the rear flap 50 to passage 12 opening and wing camber increasing position shown in full lines by Fig. 4, lowers flap 70 to its full line position 55 as shown, with flap 50 at a greater angle than the flap 70. The difference in the angle of depression or lowering of flaps 50 and 70 is carried out in the present example through the relative lengths of the cranks 72 and 73 60 to secure greater angular movement for flap 50 than for flap 70, although the invention intends other arrangements for interconnecting the flaps and other relative lowered position angles, or if desired the flaps can 65 assume the same or equal angles of depression.

70 sion. It is to be further noted here that the invention contemplates the use of a plurality of flaps such as typified by the flaps 50 and 70, but independently operable, all as coming within the generic principles of the invention.

75 The air displacement passages and/or slots may be provided of any desired length of the wing span, or the wing can be formed with any desired number of such passages and/or slots, or a plurality of both the automatic and manually operated vanes or flaps may be provided for each passage and/or slot, as desired. With the automatically operated and controlled vanes or flaps any 80 desired number of springs or equivalent means can be mounted along the span of such vanes or flaps, and so with the manually operated and controlled vanes or flaps, they may be operated from and at several points 85 along their span, the invention in no sense being restricted in such respects to either a single automatic operating means, or a single point for manual operation and control.

90 It is to be further noted that under certain conditions the automatic operation of the passage controlling means or member can be carried out without the necessity for or use of springs, and the invention recognizes 95 this fact and includes such operation within its scope, as well as other arrangements and equivalent means or mechanisms for obtaining the automatic operation within the principles of the invention.

100 While described and shown as applied to and embodied in airplane wings, the term "wing" herein and in the appended claims is employed in a broad, generic sense to include any and all lift surfaces, including control surfaces, to which the invention is applicable or may be adapted. The term "passage", as used herein and in the appended claims, is intended and to be interpreted in a broad sense to cover and include a slot or slots or any opening or space, or plurality thereof, in or on a "wing" for the displacement of air within the principles of the invention.

110 It is also evident that various changes, modifications, variations, substitutions and eliminations might be resorted to without departing from the spirit and scope of my invention, and hence I do not wish to limit myself to the exact and specific disclosures made herewith by way of example.

115 What I claim, is:

120 1. In a high lift wing, an automatically operated flap member for increasing the camber and lift of the wing, and means for releasably retaining the flap in camber increasing position.

125 2. In a high lift wing having an air displacement passage, an automatically operated flap member for opening and closing the passage and a manually controlled and 130

- operated member for opening and closing the passage, the automatic flap member caused to operate to open and close the passage by the opening and closing thereof by 5 the manual member, means for automatically retaining said flap member in passage opening position, and said means operated by the closing of the manually operated member, to release the flap member for automatic operation to close the passage. 10 3. In a wing having an air displacement passage, a manually operated pivotally mounted flap for opening and closing the discharge end of the passage, said flap in passage opening position lowered to increase the wing camber, and an automatically operable flap for opening and closing the inlet end of the passage, said automatic flap operated to open the passage by the pressure conditions established when the manually controlled flap is lowered to open the passage and increase the wing camber, and automatically operated to close the passage when the manually operated flap is raised 15 to passage closing camber decreasing position. 20 4. In an airplane wing of the variable lift type, a manually operated wing lift varying member and an automatically operating member controlled by said manually operated member for cooperation therewith to cause the wing to develop an increased lift, the operation of the manually operated wing lift varying member establishing air conditions acting on and causing operation of the automatic member in accordance with the air conditions established by the manually operated member, to increase or decrease 25 the lift developed by the wing. 30 5. In an airplane wing of the variable lift air displacement passage type, semi-automatically operating means for causing said wing to develop an increased lift, embodying an automatically operating member for opening the wing passage for displacement of air therethrough to increase the lift developed by the wing, and manually operable mechanism for controlling said automatic member to cause such member to operate, or to maintain the same against operation. 35 6. In an airplane wing of the variable lift air displacement passage type, a member automatically operated under high angle of attack conditions of the wing for opening the wing passage for displacement of air therethrough to increase the lift developed by the wing, and manually operable means for maintaining said member against wing lift increasing operation. 40 7. In a wing of the variable lift type having an air displacement passage for flow of air therethrough to cause the wing to develop an increased lift, means for opening said passage for flow of air therethrough and for 45 closing the passage against flow of air there- through, the said means embodying; an automatically operating member normally closing the passage and actuated to open the passage by flow of air therethrough, and a manually operable member for opening the passage to cause flow of air therethrough and opening of the automatic member, and for closing the passage against flow and return of the automatic member to normal passage closing position. 50 8. In an airplane wing of the variable lift type having an air displacement passage for flow of air therethrough to cause the wing to develop an increased lift, a manually controlled member for opening and closing one end of the passage, and an automatically operating member for opening and closing the opposite end of the passage, operation of the manually controlled member to open or close the passage establishing air conditions acting upon and causing operation of the automatic member to open or close the passage. 55 9. In an airplane wing having an air displacement passage for flow of air therethrough to cause the wing to develop an increased lift, a manually controlled member for opening and closing the air displacement passage, and an automatically operating member for opening and closing the passage, said automatic member normally in passage closing position with the manually controlled member in closed position and the passage inoperative to increase the wing lift, and the said automatic member caused to operate to 60 open the passage by the air flow conditions established when the manually controlled member is in passage opening position. 10. In an airplane wing having an air displacement passage for flow of air therethrough to cause the wing to develop an increased lift, automatically operating means normally in position closing said passage, and manually controlled means for operation to establish air conditions causing operation of said automatic means to open the passage and cause flow of air therethrough to increase the lift developed by the wing. 105 11. In an airplane wing having an air displacement passage for flow of air therethrough to cause the wing to develop an increased lift, a manually operated member for opening the inlet end of the passage for flow of air thereto and for closing the inlet end of the passage against such flow, and an automatically operating member for opening and closing the discharge end of the passage, said automatic member opened by the air conditions established with the manually operated member in passage opening position and closed by the air conditions established with said manually operated member in closed position. 110 12. In a variable lift wing having an air displacement passage for flow of air there- 115 120 125 130

through to cause the wing to develop an increased lift, an automatically operating member for opening and closing said passage to vary the lift of the wing, and means for 5 maintaining said member in fixed relation to the wing against automatic operation.

13. In a variable lift wing, an automatically operating member actuated by changing airflow conditions acting thereon for 10 varying the lift of the wing, and manually operated means for controlling and changing the airflow conditions acting on said member for causing operation of said member or for maintaining said member against 15 automatic operation.

14. In a variable lift wing of the air displacement passage type, an automatically operating member movably mounted on the wing for opening and closing the air displacement passage to vary the lift of the wing, and manually controlled mechanism 20 for releasably locking said member against movement.

15. In a wing, a pivoted flap member, an 25 aileron pivotally mounted on and carried by said flap member, and means for operating the aileron independently of the flap member, said aileron operating means maintaining the aileron in relative angular adjusted 30 positions with respect to the wing during movement and in all positions of the flap member.

16. In a wing, a pivoted flap member, an 35 aileron pivotally mounted on and carried by said flap member, and means for maintaining said aileron in relative angular position with respect to the wing in all positions of said flap member.

17. In a wing, a pivoted flap member, mechanism 40 for operating said flap member, an aileron pivotally mounted on and carried by said flap member, means for operating said aileron independently of said flap member, and the said aileron operating means maintaining the aileron in angularly adjusted positions relative to the wing in all positions of 45 the flap member.

18. In a variable lift wing having an air displacement passage for flow of air there- 50 through to increase the wing lift, a manually operated flap pivotally mounted on the wing for opening and closing said passage, another flap pivotally mounted on the wing for vertical swinging to and from position depending from the under side of the wing, and means operatively coupling said flaps for simultaneous operation thereof by manual operation of said first mentioned flap to swing said second mentioned flap to depending position when said first mentioned flap is swung to passage opening position.

19. In a wing having an air displacement 55 passage, a pivotally mounted flap for opening and closing the discharge end of the passage, and a member for opening and closing

the inlet end of the passage, said member automatically actuated to open the passage by the air pressure conditions established when said flap is lowered to open the discharge end of the passage, and actuated to close the passage when said flap is raised to position closing the discharge end of the passage. 70

20. In a wing having an air displacement passage for flow of air therethrough to cause the wing to develop an increased lift, a member for opening and closing one end of the passage, and a member for opening and closing the opposite end of the passage, operation of one of said members to open or close the passage establishing air conditions acting upon and causing operation of the other of said members to open or close the passage. 75

21. In a variable lift wing having an air displacement passage for flow of air therethrough to cause the wing to develop an increased lift, a pivotally mounted vertically swingable flap in normal raised position forming a portion of the normal contour of the wing and closing the discharge end of said passage, and in lowered position opening the discharge end of the passage and increasing the wing camber, a pivotally mounted vertically swingable member for opening and closing the inlet end of said passage, and said member automatically swung to open the inlet end of the passage by air conditions established when said flap swings to lowered passage discharge end opening and wing camber increasing position, and automatically swung to close the inlet end of the passage by air conditions established when said flap swings to normal raised, passage discharge end closing position. 80
